CLAIM

The ornamental design for an electronic storage box for vehicles, as shown and described.

DESCRIPTION

FIG. 1 is a top, left-side rear perspective view of the electronic storage box for vehicles showing my new design; FIG. 2 is a top, left-side front perspective view thereof; in a closed configuration with its tray up;

FIG. 3 is a top, left-side front perspective view thereof; in an open configuration with its tray down;

FIG. 4 is a rear view thereof;

FIG. 5 is a front view thereof;

FIG. 6 is a top view thereof;

FIG. 7 is a bottom view thereof;

FIG. 8 is a right-side view, wherein the left-side view being a mirror image thereof;

FIG. 9 is a closed up front perspective view of the channel-bracket connection between the electronic storage box shown in FIG. 1 and its tray; and,

FIG. 10 is a closed up rear perspective view of the channel-bracket connection between the electronic storage box shown in FIG. 1 and its tray.

The ornamental design which is claimed is shown in the solid lines in the drawings. The broken lines shown in the drawings are for the purpose of illustrating environmental structure and form no part of the claimed design.

1 Claim, 9 Drawing Sheets
